PAPER HANGER'S FOLDING TABLE

Irvin C. Reinard, Buffalo, N. Y.

Application April 29, 1947, Serial No. 744,594

2 Claims. (Cl. 311—90)

1

This invention relates to an improved portable working table such as a paperhanger's table or the like.

One of the objects of the invention is to provide an improved working table for paperhangers and the like; the table top portion being sectioned and adapted to be folded into the form of a closed carrying case.

Another object of the invention is to provide a folding table of the character described, which incorporates improved means for carrying therein the usual supply of paperhanger's tools.

Another object of the invention is to provide in a table of the character described an improved form of folding leg device which is adapted to assist in retaining the carried tools in proper pocketed positions therein.

Another object of the invention is to provide an improved table of the character described which is so arranged as to be of improved rigidity when set up for working operations thereon.

Other objects and advantages of the invention will appear in the specification hereinafter.

In the drawing:

Fig. 1 is a perspective view of a table of the invention, shown in "open" or operative condition;

Fig. 2 is a perspective view thereof when in folded or carrying condition;

Fig. 3 is a bottom plan view of the table shown in "open" position with the legs folded against the tools carried therein;

Fig. 4 is a section as along line IV—IV of Fig. 3;

Fig. 5 is a fragmentary section transversely of the table when in operative position; and

Fig. 6 is a detail of the table top bracing arrangement.

The drawings illustrate the invention in the form of a table which is particularly adapted to be used by wall-paper hangers and the like; and the table comprises a two-piece top supported by legs which may be folded inwardly under the top boards. Thus, the top construction is illustrated to comprise a pair of top boards 10 and 12 which may be formed of solid wood, or plywood, or wood conversion material, or metal, or the like; having in mind that it is desirable to use light-weight materials while constructing the table so as to be extremely rigid when in operation position. The top boards 10 and 12 are fitted with skirt boards 14 and 16, so that the top boards and the depending skirt boards comprise in effect an open box-like construction. The middle skirt boards 14 and 16 are hingedly interconnected by means of

hinges 20 (Figs. 3—4), whereby it will be seen that the table top structure may be opened as illustrated in Fig. 1 to provide a smooth overall table top of such longitudinal and transverse dimensions as to adapt the structure to wall-paper cutting and pasting purposes, as is well known in the paper hanging art. Also, the top structure may be folded by means of the hinge devices into the condition illustrated in Fig. 2, whereby a closed box-like carrying case is provided of such form as to be adapted to carry therein all of the tools usually employed by a wall-paper hanger. Latch devices 22 are provided to detachably lock together the skirt boards opposite the position of the hinges when the table is folded; and a carrying handle 24 is provided to facilitate carrying of the closed table, as in the manner of a suitcase.

To support the table top in open or operative position for wall-paper cutting and pasting purposes, a plurality of legs 26 are pivotally connected to the outside skirt boards 14 as indicated at 28. Lateral braces in the form of diagonal struts 30 and 31 are fixed to the legs as indicated at 32 and 33 and are pivoted to table top cross brace members 34, as indicated at 36. The braces 31 are so shaped as to lie across the tool carrying compartments within the case when the legs are folded inwardly. Longitudinal braces for the legs 26 are provided in the form of folding struts as indicated at 40, so that the legs may either be folded inwardly against the bottom surface of the table top boards or extended downwardly at right angles therefrom and held rigidly in such position by the braces 30, 31, and 40.

To reinforce the table top when in open operative position against downwardly bending along the hinge line, a cross brace 42 (Figs. 5—6) is provided to extend between oppositely paired legs 26. Each cross brace comprises a bar of wood or other suitable material which is lengthwise dimensioned so as to freely slip-fit between the opposite legs and up into position under the abutted skirt boards 14 (Fig. 5). To support the braces 42 vertically the legs 26 are each supplied with a straddle block 44 which is vertically slidable on the leg by means of a bolt and wing nut device 45; the blocks 44 being slotted as indicated at 46 (Fig. 6). At their upper ends the blocks 44 are forked as indicated at 48, and thus it will be understood that the blocks 44 may be loosened and lowered to permit the brace bars 42 to be inserted in operative position, and then the brace blocks are raised and clamped in position by the wing nuts 45 so that the forked portions of the blocks straddle the cross bars 42 to hold them

firmly in table top bracing position. When not in use the cross bars 42 may be readily disassembled and stowed within the interior of the folded table, to be carried along with the table from job to job.

A zinc cutting plate is preferably provided at one outside longitudinal edge of the table top structure as indicated at 50. Also, a metal straight edge as indicated at 52 (Fig. 3) is provided of such length as to fit interiorly of the table top structure, and the cross bars 34 of the table top structure are recessed as indicated at 54 so as to receive the straight edge member 52 in cradled relation therein. Thus, with the straight edge member 52 in position on the cross bars 34, as shown in Fig. 3, the table structure may then be hinged to its closed position to firmly hold the straight edge member in cradled position. Tool receiving pocket structures as indicated at 60 may also be provided interiorly of the folding structure as shown in Fig. 3, whereby the tools customarily employed by paperhangers or the like, such as scissors and brushes etc., may be conveniently mounted therein. Bolts 62 may be slip-fitted through suitable apertures in the legs 26, and the bolts are selected of such length that they may be push-pulled inwardly and outwardly relative to the legs in connection with leg-folding operations, so that when the table is opened up in operative position the bolts 62 may be pulled out as shown in Fig. 5 to provide steps upon which straight-edge tools or the like may be rested.

I claim:

1. A portable working table comprising a pair of relatively hinged table top boards having depending skirt portions extending therefrom so that when the unit is folded it provides a closed carrying case, latch means for detachably locking said case in closed position, handle means for carrying said closed case, leg means pivotally connected to said skirt portions and adjustable thereon between folded positions against said top boards and extended positions at right angles therefrom for supporting the opened table in working condition, pivoting brace means interconnecting said legs and said skirt portions for laterally bracing said legs when in extended positions, detachably mounted cross bar means adapted to slip-fit between opposite legs into position bearing upwardly against the opened table

top structure, forked blocks carried by said legs to be movable thereon and having opposite fork portions slidably engaging at opposite sides of said cross bars at opposite ends thereof to hold the cross bars upwardly against the table top and against lateral displacement from said legs, and means clamping said forked blocks to said legs so as to be positionally adjustable thereon.

2. A wall paperhanger's table comprising a pair of top boards, hinge means relatively hinging said table top boards along a fold axis, said top boards having depending skirt portions and top cross brace means extending therefrom so that when the unit is folded it provides a closed plural compartment carrying case, legs pivotally connected to said skirt portions and adjustable thereon between folded positions against said top boards and extended positions at right angles therefrom for supporting the opened table in working condition, leg brace means interconnecting said legs and said top cross brace means for laterally bracing said legs when in extended positions, said leg brace means having portions thereof formed to extend parallel to said fold axis when said legs are folded to brace loose tools packed therein against accidental displacement, detachable cross bar means adapted to slip-fit between opposite legs into position bearing upwardly against the opened table top structure, and fork means carried by said legs to be movable thereon and having opposite fork portions slidably engaging at opposite sides of said cross bars at opposite ends thereof to hold the cross bars upwardly against the table top and laterally against displacement therefrom.

IRVIN C. REINARD.
